UNITED STATES PATENT OFFICE.

BENJAMIN F. HAYDEN, OF SPRINGFIELD, MISSOURI.

CURTAIN FOR VEHICLES AND THE LIKE.

Application filed March 14, 1923. Serial No. 625,023.

To all whom it may concern:

Be it known that BENJAMIN F. HAYDEN, a citizen of the United States of America, residing at Springfield, in the county of 5 Greene and State of Missouri, has invented new and useful Improvements in Curtains for Vehicles and the like, of which the following is a specification.

The object of the invention is to provide 10 a vehicle curtain and spreader for the same together with means for mounting the curtain and spreader, so that the curtain may be held effectively in enclosing relation with the body of the vehicle and is swung at will 15 outwardly to permit egress from the vehicle, the outward or open position being maintained without attention until it is desired to swing the curtain to closed position. A further object is to provide a construction 20 of this kind which is simple, inexpensive to manufacture, and of a character adapted to remain in operating condition irrespective of the service to which it is subjected.

With these objects in view the invention 25 consists in a construction and combination of parts of which a preferred embodiment is shown in the accompanying drawings, wherein:

Figure 1 is a side elevational view of a 30 vehicle top showing the application of the invention thereto.

Figure 2 is a side elevational view of the curtain and stretcher for the same.

Figure 3 is a detail elevational view illustrating one of the supporting brackets and the side arms of adjacent curtains connected therewith.

Figure 4 is an end elevational view of the structure of Figure 3.

Figure 5 is a view similar to Figure 4 but showing the curtain in extended or raised position.

Figure 6 is a detail elevational view showing a modification of the bracket adapting 45 the same for attachment to a vertical support.

The invention contemplates the use of a curtain 1 such as that illustrated in Figure 2 of the drawings and provided with a trans- 50 parent panel 2, the curtain being carried on a U-shaped frame or stretcher 3 the legs of which terminate in rectangular eyes 4 disposed at the upper corners of the curtain and occupying spaces from which corner 55 sections or portions of the goods constitut-

ing the curtain are removed so that the eyes may lie within the area of the curtain.

The number of curtains necessary to close the open side space of the vehicle of course depends on the size or width of the curtain 60 and the length of the car. In the present illustration, however, two curtains are em- 65 ployed on each side and are supported on appropriate brackets secured to the side rail

5 of the car top 6 and to a vertical post 7 (if one is employed) and the wind shield 65 frame 8. The intermediate bracket, which is secured to the side rail, is formed pref- 70 erably from a single piece of sheet metal from which a clamping ring 9 is struck for 75

embracing relation with the side rail 5, to have its free extremities engaged by a clamping bolt 10, this clamping ring carrying a curtain supporting element on each 80 side and consisting of hanger hooks 11 75 formed by bending the material back on itself as clearly illustrated in Figures 4 and 5 of the drawing, each hanger hook is attend- 85 ed with a resilient arm 12 constituting a portion of the hanger supporting element 80 and formed in the same way as the hook, the extremity of the arm, however, being extended into overlapping relation with the free end of the hook and deflected down- 85 wardly as indicated at 13 to provide a throat 90 14 between it and the hook and terminating in a bearing foot 15. The eye 4 of the stretcher 3 engages the hook to suspend the weight of the stretcher and curtain at one 95 side and the foot 15 bears on the lower por- 90 tion of the eye, thus holding the curtain in against the side of the car. It may be 100 swung outwardly, however, as indicated in Figure 5 by applying an outward pressure to the stretcher frame, when the bearing foot 95 yields and the lower portion of the eye rides over the inclined portion 13 of the arm 12, until the lower portion of the eye assumes a position on the arm above the throat 14, when the curtain is held in a position pro- 105 jecting laterally from the machine and sub- stantially in the plane of the top which per- 110 mits ready egress and ingress. One of the curtain supporting elements on the inter- 110 mediate hanger supports the forward edge of the rear curtain and the rear end of the forward curtain. The rear end of the rear curtain may be supported from the side bar of the top by a hanger similar to the inter- 110 mediate hanger but in the illustrated em-

bodiment of the invention, the upright post is employed at the rear and provided with a supporting element similar to those on the intermediate hanger but provided with a 5 clamping element 10^a disposed at right angles to the curtain supporting element, whereas the clamping member of the intermediate hanger is parallel with the curtain supporting element. At the forward end, 10 the forward curtain is carried by a supporting element having a clamping element 10^b disposed at the proper angle for engagement with the side bar of the wind shield frame to dispose the curtain supporting element in the proper position to receive the 15 forward end of the forward curtain and permit its being swung outwardly or inwardly as in the case of the rear curtain.

Having described the invention, what is 20 claimed as new and useful is:—

1. A device for the purpose indicated comprising a swinging element provided with an eye, and a hanger therefor, the hanger having a supporting hook engaging the eye.

and an arm disposed in opposing relation 25 to the hook and having a deflected portion defining a throat at the extremity of the hook and a bearing foot engaging said eye, the arm being yieldable to permit swinging movement of said element and retaining the 30 latter in either of two positions having an approximate angular distance of 90°.

2. A device for the purpose indicated comprising a swinging element provided with a rectangular eye, a hanger having a 35 supporting hook engaging the upper side of the eye and a spring arm disposed in opposing relation to the hook and having a bearing foot engaging the lower side of said eye for deflection by the latter, the arm being yieldable to permit swinging movement of said element and to retain the latter in 40 either of two positions having an approximate angular distance of ninety degrees.

In testimony whereof he affixes his signature:—

BENJAMIN F. HAYDEN.
